UNITED STATES PATENT OFFICE

WILLIAM D. KYLE, OF MILWAUKEE, WISCONSIN, ASSIGNOR, BY MESNE ASSIGNMENTS,
TO LINE MATERIAL COMPANY, OF SOUTH MILWAUKEE, WISCONSIN, A CORPORA-
TION OF DELAWARE

INSULATOR RACK

Application filed January 29, 1927. Serial No. 164,606.

This invention relates to certain new and useful improvements in insulator racks of the type particularly designed for supporting secondary wires and has as an object the provision of a rack which is extremely simple in construction, efficient in operation and capable of production at comparatively low costs.

Another object of this invention resides in the provision of an improved rack of the character described in which the insulator proper is in compression at all times thereby increasing its strength and obviating the necessity of steel arm members to protect the same against side pulls.

Another object of this invention resides in the provision of an improved insulator in which the wire contacts only with the smooth porcelain member, all sharp edges of the metal securing means which are apt to injure the wire when stringing the same being imbedded in the porcelain.

Another object of this invention resides in the provision of an improved insulator so constructed that breakage of the porcelain allows the wire to drop rather than grounding the same to the frame.

Another object of this invention resides in the provision of an improved rack of the character described in which provision is made for threading a wire through a hole therein and having means for otherwise tying a wire thereto.

A further object of this invention resides in the provision of an improved insulator rack of the character described, the bracket or base member of which is of substantially tubular shape having a portion of its face struck back upon itself to provide a double thickness for the reception of the insulator mounting bolts.

A still further object of this invention resides in the provision of an improved insulator rack of the character described, in which the position of the upper insulator on the base member is such that it would be substantially impossible for a line man standing on the upper insulator to form a circuit to the metal base member.

With the above and other objects in view

which will appear as the description pro-

ceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best modes I have so far devised for the practical application of the principles thereof, and in which:

Figure 1 is a side view, partly in section and partly in side elevation, of a rack embodying my invention;

Figure 2 is a front elevational view of one end portion of my rack, and

Figure 3 is a transverse sectional view taken through Figure 2 on the plane of the line 3—3.

Referring now more particularly to the accompanying drawing, the numeral 5 designates a bracket or base member formed from sheet metal and of substantially tubular construction having a top wall 6, and depending flanges 7 forming side walls, the longitudinal marginal portions of which are directed inwardly, as at 8, to increase the rigidity of the bracket member. The wall 6 of the bracket member is apertured, as at 9, for the reception of lag screws or bolts for mounting the bracket member to a support such as a pole, the side of a building or the like.

At the adjacent points where the insulators 11 are to be mounted, the top wall or face 6 of the bracket member is apertured and struck back upon itself, as at 10, to provide sufficient thickness to firmly anchor the threaded ends of insulator mounting bolts 12. Each insulator 11 is preferably formed from porcelain and of substantially oval shape in transverse section having two spaced beads 13 extending therearound to provide a central channel or groove 14 with which a transverse opening 15 extending through the insulator registers, a transverse channel 16 being formed in the material between the opening 15 and the outer end of the insulator

to receive a wire 17 applied thereto as shown in Figure 1.

Bores 18 extend through the insulator on opposite sides of the opening 15, the outer ends of which are counter-bored, as at 19, to accommodate the heads 20 of the bolts 12, the inner ends 21 of which are threaded in the registering internally threaded openings in the wall 6 and the struck-up portions 10 of the base member. The bolts 12 hold the insulator with its base snug against the bracket member, thereby placing the porcelain in compression at all times and materially increasing its strength.

15 The supporting bracket member having relatively little depth and having its upper end on a plane lower than the top of the upper insulator precludes its use as a support by persons working on the primary wires there-
20 above and thus prevents their electrocution by the current which would run through their bodies and through the bracket. In addition, should the porcelain insulator break the wire drops rather than being held by
25 some metal portion which would wear away its insulation and possibly cause a short circuit, the dropping of the wire also providing a positive indication of breakage to insure prompt repair.

30 What I claim as my invention is:

1. In a device of the character described, a channel base member having a portion of its front wall struck out and bent back upon itself to give a double thickness to said wall, an insulator adapted to engage the base at said point of double wall thickness, and a securing bolt for said insulator threaded in the base member front wall at its point of double thickness.

40 2. A device of the character described, comprising a base member adapted to be secured to a support, an insulator adapted to be secured to the base member with its bottom flush thereagainst and having an opening extended transversely therethrough to provide means for receiving a conductor, and securing bolts passing through the insulator at each side of said opening and connected
45 with the base member, said bolts being embedded in the insulator and said insulator having a portion thereof extended beyond the base member whereby a line man, standing on the insulator, does not come in contact with the base member.

55 3. A device of the character described comprising a base member adapted to be secured to a support, an insulator having a transverse opening through which a line wire
60 may be inserted to be supported by the insulator and having longitudinal bores extending through the insulator at each side of the transverse opening, the outer ends of the bores being counter-bored, and securing
65 screws passed through the longitudinal bores

with their heads positioned within the counter-bores and their ends threaded in apertures in the base member to secure the insulator to the base member, whereby breakage of the insulator permits the line wire to drop.

70 In testimony whereof I hereunto affix my signature.

WILLIAM D. KYLE.
